MASON'S GUIDE

George Stevens, Campbell, Ohio, assignor of one-third to Pete Parthemos, Youngstown, Ohio

Application January 29, 1945, Serial No. 575,147

2 Claims. (Cl. 33—86)

1

This invention relates to a mason's guide and more particularly to devices for establishing a line between corners of masonry construction by which the mason may be guided in laying subsequent layers of masonry.

The principal object of the invention is the provision of a pair of spring tensioned guide line brackets thereto with a section of guide line to establish a mason's guide.

A further object of the invention is the provision of a mason's guide consisting of an appropriate length of guide line and means affixed to the guide line for tensioning it and holding it in appropriate position on masonry construction.

A still further object of the invention is the provision of a bracket adapted to be positioned on a corner of a masonry wall and having means formed therein for snubbing and holding the line used in connection therewith.

The device shown and described herein has been designed to facilitate the placement of a guide line as used in masonry construction work whereby a guide line is positioned from the pre-built corner portions of masonry walls across the area therebetween to form a guide for the laying of masonry units in the formation of a course of masonry thereacross. The device of the invention consists of an appropriately shaped bracket adapted to overlie a corner of the masonry construction and to be retained in such position by means of a guide line stretched between a pair of the devices, one on each corner of the wall area being formed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the mason's guide showing one portion thereof in plan view and the other portion thereof in cross section.

Figure 2 is an enlarged cross section of one of the pair of devices comprising the mason's guide shown in Figure 1.

Figure 3 is a top plan view of the mason's guide illustrated in Figure 2.

Figure 4 is a bottom plan view of the mason's guide illustrated in Figure 2.

Figure 5 is a side elevation of a section of

2

masonry wall under construction and illustrating a pair of the mason's guides in position thereon holding a guide line therebetween.

By referring to the drawing and Figure 1 in particular it will be seen that the mason's guide consists of a pair of similarly formed, appropriately shaped body members 10 and 11, each of which is provided with an offset portion 10A and 11A, respectively, and each of which is provided with a clamping member 12 and 13, respectively. The clamping members 12 and 13 are affixed to the body members 10 and 11, respectively, by means of screws 14 and 15. Each of the body members 10 and 11 is also provided with a channel formed in one side thereof. By referring to the right hand portion of Figure 1 of the drawing the channel may be seen to be axially extending of the body member 11 and is indicated by the numeral 16. An inclined passageway 17 is also formed in each of the body members and it will be observed that the free end 18 of the clamping member 13 covers the uppermost end of the inclined passageway 17 in a manner so that a guide line such as that indicated by the numeral 19 will be held thereby when positioned through the inclined passageway 17 in the manner illustrated.

By referring to Figures 2, 3 and 4 of the drawing enlarged detailed views of the body member 11, which is identically formed with the body member 10, may be seen. It will be observed that when the body members 10 and 11 are operatively positioned on a section of guide line such as that indicated by the numeral 19 and the body members 10 and 11 positioned in oppositely disposed relation to one another, the guide line 19 will normally lie in the channel 16 and be snubbed by reason of the angular location of the passageway 17 which is formed between the innermost portion of the channel 16 and the opposite side 40 of the body member 11 and terminates, as heretofore described, beneath the outermost or free end 18 of the clamping member 13. Double snubbing action is imparted to the guide line 19 by the angular positioning of the passageway 17 as the 45 guide line 19 is caused to make two abrupt turns over relatively sharp corners. This snubbing action is insured by the holding action imparted to the guide line 19 by the free end 18 of the clamping member 13.

It will thus be seen that when a pair of the body members 10 and 11 are positioned in operative position on a section of guide line the body members may themselves be positioned on the opposite corner of a masonry construction as illustrated in Figure 5 of the drawing.

By referring now to Figure 5 of the drawing it will be observed that a completely finished lower course of masonry units is indicated by the numeral 20 and that on each end thereof partially finished corners 21 and 22 have been laid. The body members 10 and 11 have been positioned so that the guide line 19 stretched therebetween serves to hold them upon the corners as their extensions 10A and 11A, respectively, engage the sides of the corners and the body members 10 and 11 are held in such position by the guide line 19. It will be seen that the guide line 19 thus forms a horizontal guide for the laying of the subsequent course of masonry units and that when the course is finished the nature of the body members 10 and 11 readily enables them to be released in the guide line sufficiently to permit them to be re-installed on the next course above. It will be seen that a mason may readily install the guide line through the use of the body members 10 and 11, placing one near the end of the guide line being used and positioning it on the corner as shown in Figure 5 and then subsequently positioning the other body member on the opposite corner, in oppositely disposed relation, and manually tightening the guide line which will be automatically retained in tightened position by the construction of the body members themselves.

It will thus be seen that a simple and efficient mason's guide has been disclosed which may be economically formed and hence widely distributed.

Having thus described my invention, what I claim is:

1. A pair of body members and a section of guide line forming a mason's guide, each of the body members consisting of a section of material having a projection formed on one end thereof at right angles thereto to form a bracket for engaging a masonry corner, an axially extending channel formed in the said section of material and an angular passageway through said section of material, the said channel and passageway providing for the reception of the said guide line and for snubbing said guide line, a leaf spring affixed to the said section of material and normally engaging the said guide line, so as to hold it against slipping in the passageway to insure the snubbing action.

2. A pair of body members and a section of guide line forming a mason's guide, each of the body members consisting of a section of material having a projection formed on one end thereof at right angles thereto to form a bracket attachable to a masonry corner, an axially extending channel formed in the said section of material and an inclined passageway through said section of material, the said channel and inclined passageway providing for the reception of the said guide line so as to snub the said line thereby, a leaf spring affixed to the said section of material, the free end of the said leaf spring covering the end of the said inclined passageway opposite the said channel so that a guide line positioned therethrough will be held thereby.

GEORGE STEVENS.
